Primary Examiner — Susan M Lee(74) *Attorney, Agent, or Firm* — Polsinelli Shughart PC(57) **CLAIM**

I claim the ornamental design for a bird feeder, as shown and described.

DESCRIPTION

FIG. 1 is a front view of a bird feeder, the rear view being identical;

FIG. 2 is a side view of the bird feeder, the opposite side view being a mirror image thereof; and,

FIG. 3 is a bottom view thereof.

The elements depicted in broken line are not claimed.
